(57) **CLAIM**

The ornamental design for a plastic diagnostic card, as shown and described.

DESCRIPTION

The nature and intended use of the article in which the design is embodied represents the new order in design of diagnostic devices directed toward remote identification of specific chemicals, elements and drugs in fluids and the atmosphere.

FIG. 1 is a front perspective view of a plastic diagnostic card showing my new design;

FIG. 2 is a front elevational view thereof;

FIG. 3 is a right side elevational view thereof;

FIG. 4 is a back elevational view thereof; and,

FIG. 5 is a left side elevational view thereof.

FIG. 6 is a top plan view thereof; and,

FIG. 7 is a bottom plan view thereof.
